P. JUBIEN.
ORE AND LIKE SEPARATING MEANS.
APPLICATION FILED APR. 5, 1912

UNITED STATES PATENT OFFICE.

PIERRE JUBIEN, OF SAN FRANCISCO, CALIFORNIA, ASSIGNOR OF ONE-HALF TO P. A. BRANGIER, OF AGNEW, CALIFORNIA.

ORE AND LIKE SEPARATING MEANS.

1,072,733.

Specification of Letters Patent. Patented Sept. 9, 1913.

Application filed April 5, 1912. Serial No. 638,609.

To all whom it may concern:

Be it known that I, PIERRE JUBIEN, a citizen of France, residing in the city and county of San Francisco and State of California, have invented new and useful Improvements in Ore and Like Separating Means, of which the following is a specification.

My invention relates to a means for the dry separation of ores.

10 It consists in allowing finely pulverized materials of different gravities to fall through calm air and be received upon a constantly moving surface at such a distance below that the heavier particles will 15 be received upon one part of the table or surface, and the lighter particles which will arrive later, will fall upon the part behind that receiving the heavier portion.

The invention consists of the parts and 20 the construction and combination of parts as hereinafter more fully described and claimed, having reference to the accompanying drawing, in which the figure is a perspective view illustrating my invention.

25 This invention depends upon the difference in the time of falling of particles pulverized to the same degree of fineness and depends upon the following principles which underlie the method: In pulverized 30 metal-bearing rocks there is for each kind a special degree of fineness at which the pulp is composed of grains of ore and grains of gangue individually pure and free from each other. So long as such a degree of 35 fineness is not reached, i. e., with grains of greater size, the gangue and the ore co-exist in each grain. As far as the usual metals are concerned the ore is, in most cases, of a higher density than its gangue.

40 Two bodies of the same dimension but of different densities being dropped from a given height at the same time would likewise reach the ground at the same time if the fall should take place in a vacuum. If, 45 however, the fall be effected in calm air, and provided the dimensions of the two bodies are small enough, the resistance of the air will cause the denser body to reach the ground first. The intervals of time between the arrivals of the two bodies will 50 increase with the difference in densities and the height of fall. If, therefore, a pulp of a certain degree of fineness is to lie in a box having for its bottom a screen, the mesh size of the screen can always be chosen a

little bigger than that of the grains, but just enough however to prevent any one grain from escaping the meshes as long as the screen is kept perfectly motionless. If now a gentle knock be given the frame, it 60 would instantly cause one grain to escape from most of the meshes, and if the mesh size has been properly selected only one grain will escape from each mesh until another knock or disturbance is given. 65

The metal-bearing rock is crushed and pulverized to a degree of fineness at which the pulp consists almost exclusively of grains of individually pure ore or gangue. The grains are then made practically isometric, i. e., divided in several heaps in each of which all grains are about of the same size. This may be obtained by successively sifting the pulp on sieves of increasing fineness. Obviously, by such process the pulp run through a certain sieve will be composed exclusively of grains smaller than the meshes of this sieve and larger than those of the next finer sieve upon which they will have been retained. 75 Such grains having the size between the sizes of the meshes of two consecutive sieves, I call isometric, and for the sake of brevity I likewise call isometric a pulp composed of such isometric grains. Although absolute isometry may never be reached, it is approachable as closely as needed. The result of the successive sifting, above described, is to divide the pulp into as many heaps as sieves are used, and at this stage 80 of the process each heap is ready for operation by my apparatus, which I call a catarborizer. 85

My invention may be carried out by an apparatus which is shown in the accompanying illustration. 95

As here shown, A is a vertical shaft which may be rotated at a regular velocity of a few revolutions per minute by any suitable power. This shaft drives at its lower part 100 a circular open receiver, which is here shown as divided into two sectoral parts F and F' which are shaped like funnels. Surrounding the upper part of the shaft and having a central opening through which the shaft turns freely are a number of sectors S. Each sector is, in fact, an open box-shaped structure having for a bottom a screen, and, as here shown, these sectors are arranged around a common center, thus forming a 105 110

- series of receptacles which taken together form a complete circular receiver. The pulp may be fed into one of these boxes having a screen so selected that the pulp will stay upon it, and a knock given the frame at regular intervals will cause a grain to escape from each mesh with each knock. The center of the screen is about the axis of the shaft and its diameter is substantially the same as that of the receiver F below. Each of the sectors S composing the screen is independent, that is, it has no point of contact with its neighbors, and, as already stated, the shaft revolves in the middle of the screen without touching it. The pulp to be concentrated is fed to each sector by any suitable feeding means. As here shown a hopper 2 is provided with a series of distributors 3 through which the material may pass.
- In order to produce the desired knock, I have shown a rod 4 suspended in line with the outer periphery of the sectors, and it may have a weight or protuberance, as at 5, sufficient to produce the desired knock. Just beneath the screen is a rod R fixed to the shaft A. This revolves with the shaft, and as it passes each of the suspended swinging arms 4, it will push the arm outward, as shown in dotted lines, and passing will allow it to swing back and give the sector a gentle knock. This causes grains to fall from each of the screen openings, and as they are substantially isometric, those which are of pure ore being heavier will arrive at the level of the receiver considerably before the lighter grains of gangue and will thus find their way into the funnel F; the gangue grains arriving subsequently at the same level but the revolution of the shaft has driven away the funnel F and placed the funnel F' instead. As the respective positions of the rod R and the funnels are fixed, the same of course occurs for each sector in turn, and all the sectors drop the grains which are segregated by fall and collected separately in the funnel. From the funnels the ore and the gangue grains are led into their respective places of storing.
- The above description illustrates a convenient means to carry out my invention, but it will be understood that other equiv-

alent arrangements of the apparatus may be employed with a like effect.

Having thus described my invention, what I claim and desire to secure by Letters Patent is—

1. In a device of the class described in combination, an annular series of adjoining independently agitable screens for feeding sized material, a rotatable sub-divided receptacle directly beneath the annular series of screens but placed a substantial distance below the same, means for agitating each of said screens in succession, means for rotating the receptacle to bring its compartments successively beneath each screen, and means synchronizing the period of successive agitation of each screen with the rotation of said receptacle. 70

2. In a device of the class described in combination, a plurality of independently agitable screens for feeding sized material, a sub-divided receptacle movably mounted directly beneath the said screens, but placed a substantial distance below the same, means for independently agitating each screen, means for moving said receptacle to bring its compartments successively under each screen, and means for synchronizing the period of agitation of said screens with the movement of said receptacle. 75

3. In a device of the class described, an annular series of independently agitable screens for feeding sized material, a rotatable sub-divided receptacle directly beneath the annular series of screens but placed a substantial distance below the same, a plurality of agitators comprising vertically suspended rods, one being suspended adjacent each screen, a vertical shaft for rotating said receptacle, and agitator arms for said agitators mounted on said shaft and adapted to operate said agitators in synchronism with said receptacle as the said shaft is rotated. 90

In testimony whereof I have hereunto set my hand in the presence of two subscribing witnesses.

PIERRE JUBIEN.
